UNITED STATES PATENT OFFICE.

ROY J. WINSOR, OF MILWAUKEE, WISCONSIN, ASSIGNOR TO WEHR CO., OF MILWAUKEE, WISCONSIN, A CORPORATION OF WISCONSIN.

THROTTLING GOVERNOR FOR TRACTORS.

Application filed April 11, 1922. Serial No. 551,637.

To all whom it may concern:

Be it known that I, Roy J. WINSOR, a citizen of the United States, and resident of Milwaukee, in the county of Milwaukee and State of Wisconsin, have invented certain new and useful Improvements in Throttling Governors for Tractors; and I do hereby declare that the following is a full, clear, and exact description thereof.

10 The invention relates to devices for tightening a fan belt on a motor vehicle and throttling the intake of explosive mixture to control the operation of the motor. It is designed more especially for Fordson tractors.

It comprises a throttling governor, the case of which forms an idler pulley adapted to tighten a fan belt. Means influenced by a spring are provided for supporting the 20 pulley for tensioning operation, and means are provided for cooperating with the governor to control a throttle.

A primary object of the invention is simplicity of construction, and ease of manufacture.

The parts are adapted to perform a dual function. The governor case operates to house the governor and to tension the belt and the supporting means for the case supports, also the mechanism for controlling the throttle.

A very important object of the invention is readiness and convenience of installation. The mechanical operation of the timer is not disturbed nor altered in any manner, the motor is not retimed, the location of the timer is not changed, and the regular butterfly valve, gas throttle and other levers remain intact; no holes are drilled. The 40 manner of installation is simple, not calling for an expert mechanic. The mere loosening and tightening of two cylinder head cap screws suffice for positioning the governor in place.

45 In addition to its functions in controlling the motor, the governor performs the additional function of acting as a belt tightener. The governor case forms the idler pulley, running against the slack side of the belt. The case is light in weight and requires very slight pressure against the belt to drive it. The tension of a spring holds the governor tightly against the fan belt and takes up the slack as the belt stretches. 50 This prevents any possible slippage of

either governor or fan. A water or oil soaked belt will not effect its operation.

With the above and other objects in view which will appear as the description proceeds, my invention resides in the novel 60 construction, combination and arrangement of parts substantially as hereinafter described and more particularly defined by the appended claims, it being understood that such changes in the precise embodiment 65 of the herein disclosed invention may be made as come within the scope of the claims.

In the accompanying drawing, I have illustrated one complete example of the 70 physical embodiment of the present invention constructed according to the best mode I have so far devised for the practical application of the principles thereof, and in

which:

Figure 1 is a side elevation of the installation, parts being shown in section.

Figure 2 is a detail of the auxiliary connection housing the auxiliary throttle.

Figure 3 is a front elevation showing the 80 position of the fan and belt in dotted lines, and

Figure 4 is a detail showing the auxiliary connection in section and an extension for the hot air tube.

To cylinder head 10, support 11 is secured by means of cap screws 12-12'. It carries bolt 13 on which arm 14 is pivoted and prevented from movement on the longitudinal axis thereof, by the head of the 90 bolt. The arm is provided with a socket portion 15, apertured and operating to support governor case 16 which contacts with the fan belt 17 and rotates on bearings 18. Arm 14 is permitted lateral movement, and spring 19, contacting with lug 20 on arm 14, and bearing against nut 21, threaded on rod 22 carried by bracket 23 secured to the fan shaft 24 by nut 25, moves arm 14 laterally, causing governor case 16 to tighten 100 belt 17. Cup 26, rigid with arm 14, houses plunger 27, the position of which is determined by screw 28, having a manually manipulable knurled head 29, the screw having threaded relation with cup 26. Wing nut 105 30 locks screw 28 securely. Plunger 27 bears against spring 31, and moves the upper arm of lever 32 rearwardly, the arm pivoting at 32' on lug 32''. The end of the lower arm carries a contact 33, adapted 110

to cooperate with the end 34 of spindle 35, provided with a collar 36, against which fingers 37 of the governor are adapted to contact the fingers moving rearwardly when 5 weights 38 are directed outwardly by centrifugal force, the weights being integral with fingers 37 and the parts rotating on pivots 39, so that on rapid travel of belt 17, the governor operates to move contact 10 33 rearwardly and arm 32 forwardly, the arm being secured to rod 40, its position on the rod being determined by jamb nut 41.

Rod 40 is secured by pivot 41 to lever 42 which operates thru the medium of spindle 15 43 to control the position of butterfly 44 in auxiliary connection 45, which is received between throttling valve housing 46 and intake manifold 47, the parts being secured together by studs 48. Extension 49 is positioned in hot air tube 50. Thus mixing chamber 51, the regular butterfly, the gas throttle and other levers and the various mechanical parts, remain substantially unaltered.

25 It will be noted that the movement of arm 14 in taking up slack of belt 17, does not disturb the controlling operation of the governor, the relation of lever arm 32 and rod 40 being such as to permit the accurate and 30 reliable control of the throttle in spite of lateral movement of the governor case. Also when the governor is operative and lever arm 32 moves rod 40 to control the throttle, the governor case 16 continues performing 35 its tightening action. The case is light in weight and requires very slight pressure against the belt to drive it. This makes the governing action reliable. As the belt stretches, the slack is automatically taken 40 up. There is no possible slippage of governor or fan. Below a certain speed, the control of the motor is by the hand throttle, as in the normal operation.

I claim:

45 1. The combination of a belt tightener including a pivotally mounted support, a pul-

ley carried thereby, a governor driven by said pulley and having an operative portion located adjacent the pivot point of said support, and means connected with such operative portion and extending outwardly therefrom. 50

2. In a device of the type described, the combination of a belt, a support pivotally mounted at one end, an idler pulley carried by the other end of said support and adapted to engage said belt, a spring urging said support into belt tightening position, a governor operated by said pulley, means operated by said governor and carried by said support and having a movable portion located adjacent the pivoted end of said support, and a control link extending from the movable portion of said means, whereby the position of said control link is controlled by said governor and is substantially independent of the angular portion of said support. 60

3. In a device of the class described, the combination of an idler pulley operative for tightening a belt, said pulley being hollow, a governor therein, a support for said pulley and said governor, means for maintaining said pulley in contact with a belt, and means cooperating with said governor for throttling the supply of explosive mixture. 70

4. In a device of the class described, the combination of a pulley for tightening a belt, a governor driven thereby, a swinging support carrying said pulley and governor at its free end, means pivotally supporting said swinging support, means tending to rock said swinging support in one direction, a lever pivoted to said swinging support and having its position controlled by said governor, and control means controlled by said lever, and extending outwardly therefrom. 80

In testimony that I claim the foregoing I have hereunto set my hand at Milwaukee, in the county of Milwaukee and State of Wisconsin.

ROY J. WINSOR.
